UNITED STATES PATENT OFFICE.

HARRY LYON, OF BROCKTON, MASSACHUSETTS, ASSIGNOR, BY MESNE ASSIGNMENTS, TO UNITED SHOE MACHINERY COMPANY, OF PATERSON, NEW JERSEY, A CORPORATION OF NEW JERSEY.

SKIVING-MACHINE.

1,080,227.

Specification of Letters Patent.

Patented Dec. 2, 1913.

Application filed January 21, 1910. Serial No. 539,426.

To all whom it may concern:

Be it known that I, HARRY LYON, a citizen of the United States, residing at Brockton, in the county of Plymouth and State of Massachusetts, have invented certain new and useful Improvements in Skiving-Machines, of which the following is a specification.

This invention relates to machines for 10 skiving or beveling the edges of leather, or other similar flexible stock.

The invention is shown, and will be herein described, as embodied in a machine of the same general type as that disclosed in United States Letters Patent, No. 220,906, dated October 28, 1879. Such machine, and others of this type usually comprise as their principal parts, a rotatory knife or cutter, feed roll or drum for feeding the stock to such 20 knife, a feeding disk to coöperate with the roll or drum in the feeding operation, an edge gage to guide the stock, and a presser. The stock is introduced between the periphery of the feed roll and the face of the feed disk; through the combined action of which devices it is fed to the knife to be thereby skived or beveled; and the edge gage and presser are relied upon during such operation to properly direct the stock and to hold 25 that portion of the edge which is to be skived or beveled against the periphery of the feed roll. One objection to machines of the character referred to is that the feeding devices sometimes fail to advance the stock 30 accurately to the cutter, as the stock will often exhibit a tendency to move away from the edge gage, and, as a consequence will be skived unevenly, and frequently spoiled. In order to prevent this it is necessary that the 35 operator exercise a great amount of care in holding the stock with its edge against the gage, from the moment that he introduces it into the machine until the completion of the skiving operation, and even then it sometimes happens that a piece of stock will be 40 moved away from the gage, and either be badly injured, or spoiled.

With a view to overcoming this objection to such prior machines, a very important object of the present invention is to provide 45 means for maintaining the leather or other stock in contact with an edge gage while

such stock is being fed to the knife or cutter. Preferably, such means is also adapted to assist in advancing the stock to the knife, 55 and to this end it may consist of a device which is located in suitable coöoperative relation with the usual main feed roll of the machine, and whose construction and arrangement are such that it acts in conjunction with said feed roll in feeding the stock toward the knife, as well as acting to hold the stock against the edge gage.

In the machine herein selected for illustration the means referred to is in the form 65 of an auxiliary feed roll, which is supported above the main feed roll with its periphery suitably spaced therefrom; the axis of the auxiliary feed roll being arranged, preferably, at right angles to the axis of the main feed roll. As shown herein, also, the periphery of the auxiliary feed roll is beveled, and its face is scored or roughened in order 70 that it may aid in feeding the stock in the manner heretofore explained. The axis of 75 the said auxiliary feed roll may be conveniently supported upon a carrier in the form of a yoke between the arms of which the roll will be mounted, and said yoke may have an extension to be supported, adjustably, by a 80 member having a rocking or pivotal connection with the frame of the machine. A spring, or other yielding device, may be arranged to act on the supporting yoke or carrier in a manner to press the auxiliary roll 85 down upon the stock, but of such strength as to yield readily to permit stock of varying thickness to be fed to the knife.

Another feature of the invention consists in supporting the edge gage upon the same 90 carrier which supports the auxiliary feed roll, whereby, as said roll yields, more or less, in response to variations in the thickness of the stock, the gage will follow the movements of the roll and be maintained in 95 the same position thereon relatively to the upper surface of the stock.

Other features of the invention, including important details of construction and combinations of parts, will be hereinafter more 100 particularly described and claimed.

In the drawings: Figure 1 represents, in side elevation, a machine embodying the present invention, Fig. 2 represents an end

elevation of the same, Fig. 3 is a detail view showing the knife and its supporting and adjusting devices, Fig. 4 is a detail view, showing, in plan, the auxiliary feed roll and its allied parts, Fig. 5 is a vertical cross sectional view on the line 5—5, of Fig. 4, and Fig. 6 is a detail view of the edge gage.

The main frame of the machine 1, is shown as carrying spaced bearings, 3, 3, 10 for the driving shaft 2, having fast thereon the pulley 5 which is adapted to receive power, through a belt, from any suitable source. The shaft 2 is also shown as having thereon the fast pulleys, 7 and 9, which 15 are adapted to receive suitable belts for conveying power, respectively, to the rotatory skiving knife and to the auxiliary feed roll, as will be described later. A feed roll or drum 11, which also acts as a work 20 support, is shown as being composed of a smooth cylindrical portion 61, and a scored or roughened frusto-conical portion 63, and is keyed or otherwise fastened to the shaft 2, at or near the opposite end thereof to that 25 carrying the pulleys, said feed roll being hereinafter referred to as the main feed roll.

The main frame 1 is shown as supporting a secondary frame or casing 4, through a wall of which passes a stud 23, having 30 thereon a rotarily adjustable split clamping collar 21. The stud 23 carries at one end a head, or nut, 24, and at its opposite end is provided with threads to receive a nut 24', which serves to adjustably clamp 35 the collar 21 between the head 24 and the casing 4, suitable spacing washers being interposed between the collar and casing, as shown. The split collar 21 has internally threaded lugs to receive a screw 20, and said 40 collar embraces the stem 19 of a split clamping collar 17, which is provided with internally threaded lugs to receive a screw 18. The stem 16 of a yoke 15 is adjustably supported in the collar 17, and the arms of this 45 yoke are shown as supporting bearings for the shaft 12, which carries a fast pulley 25, and a skiving knife 13, said parts being located, respectively, upon opposite sides of the bearings in the yoke.

50 The skiving knife herein illustrated is of conical, or dished form, but it is to be understood that any other form of knife may be employed, as, for instance, the ordinary flat or disk knife as shown in the Letters Patent hereinbefore referred to. As shown in Fig. 2, the knife 13 is supported with its cutting edge in suitable proximity to the perimeter of the feed roll 11, and the adjustments afforded by the rotary clamping 55 collar 21, and the clamping collar 17, permit the knife to be set in proper position relatively to the feed roll 11 as the edge of the knife wears away, and also permit the knife to be raised and lowered with respect to the roll to accommodate stock of 60

varying degrees of thickness. The knife 13 may be rotated by any approved means, as for instance by a belt which passes from the fast pulley 7 over any suitable arrangement of idler pulleys to the fast pulley 25. 70

The casing 4 is shown as perforated to receive a stud 38, which may be clamped to the casing by a nut 38'. The stud 38 serves as a pivotal support for an arm 40, which is formed or provided with a split clamping collar 42, having threaded lugs to receive an adjusting screw 44. The collar 42 receives the stem 46 of a split clamping collar 48, which is provided with threaded lugs to receive an adjusting screw 50. A yoke 27 carries spaced bearings 28 which support a shaft 29, having fast thereon the auxiliary feed wheel 30 and its pulley 32, said feed wheel and its pulley being, as shown, arranged between the arms of the yoke with the axis of the feed wheel 30 at right angles to the axis of the main feed wheel 11. The periphery of the auxiliary feed wheel is preferably beveled on a suitable angle, and provided with a plurality of inclined scores or incisions in order to enable it to frictionally engage the smooth surface of a piece of leather, or other stock, and feed it in a manner which will be described later. The yoke 27 is shown as having an extension or stem 27' which is adjustably received within the clamping collar 48, and a bent rod 28 extends rearwardly from the stem 27' and is connected to one end of a spring 56 whose opposite end is connected to a rod or other form of bracket 54, clamped to the casing 4. A suitable stop, herein shown as a screw 52 which is threaded in a bracket secured to the casing 4 and provided with a lock nut 52', is arranged to be engaged by the end stem 27' of the yoke and to adjustably limit the distance at which the auxiliary feed wheel is normally maintained from the periphery of the main feed wheel. The weight of that portion of the yoke 27 which lies on the left hand side of its pivotal support, together with the spring 56, will tend to hold the auxiliary feed wheel down upon the stock, while permitting said wheel to yield, more or less, according to the thickness of the stock as it is being fed to the knife. 115

The auxiliary feed wheel, in the arrangement shown, is driven from the main drive shaft 2 through a belt 58, which passes over the pulley 9 on said shaft, and the pulley 32, and which may also pass over idlers 59, herein shown as rotatively supported upon arms 60, which are clamped to the casing 4, and have their outer ends secured by suitable set-screws in a block 61. 120

An arm 34 is secured to the yoke 27, and is shown as being provided with an angularly bent extremity 35, to constitute an edge gage. The edge gage 35 preferably 130

lies with its upper face closely adjacent to the beveled periphery of the feed wheel 30, while its stock-engaging face is closely adjacent to the inner edge of the feed wheel 11, and a lug 36 is formed on or secured to the gage and fits snugly against a face of the feed wheel 30, as shown in Fig. 1.

In the operation of the machine, when power is applied through a belt or other appropriate means to the shaft 2 so as to rotate the main feed wheel in the direction indicated by the arrow in Fig. 2, the auxiliary feed wheel will be caused to rotate in the direction indicated by the arrow in Fig. 1, and the skiving knife will, through suitable connections with said shaft, be driven in the proper direction to skive the stock. The leather or other stock may now be introduced between the main and auxiliary feed wheels from the right side of the machine as viewed in Fig. 2, with the edge to be skived positioned against the edge gage. The stock will then be fed to the knife through the combined operation of the two feed wheels, the action of the wheel 11 being to advance the stock toward the knife in the usual manner, while the wheel 30 frictionally engages its opposite surface and acts to impart a combined lateral, and forward movement to the stock, whereby to maintain its edge against the gage 35, and to also aid in feeding it to the knife. As the stock varies in thickness the auxiliary feed wheel will be permitted to yield through the pivotal connection of the yoke or carrier 27 with its support, but said wheel will be automatically held down upon the stock by the spring 56, and the weight of the yoke and devices carried thereby, and will thus prevent the stock from rising or curling up, prior to the action thereon of the skiving knife. In view of the fact that the edge gage is supported by the yoke 27, said gage will follow these movements of the auxiliary feed wheel and hence always be maintained in the same relation therewith, irrespective of the thickness of the stock being skived.

The collar 42 may be released from clamping engagement with the stem 46, to permit vertical adjustment of the auxiliary feed wheel so as to locate it the desired distance above the main feed wheel, and the collar 48 may be similarly released from clamping engagement with the stem of the yoke 27 to permit rotary adjustment of the yoke in order that the beveled edge of the auxiliary feed wheel may be set at the desired angle to the periphery of the main feed wheel 11.

Having thus described my invention, what I claim as new and desire to secure by Letters Patent of the United States is:

1. In a machine of the class described, the combination with a skiving knife, of a gage, and a device mounted for rotary movement in a plane substantially transverse to that

in which the stock is fed to the knife and arranged to advance the stock and to hold it against the gage.

2. In a machine of the class described, the combination with a skiving knife, of a gage, 70 feeding means for the stock, and a device mounted for rotary movement in a plane substantially transverse to that in which the stock is fed to the knife and arranged to impart a combined forward and lateral 75 movement to the stock to maintain it against the gage.

3. In a machine of the class described, the combination with a skiving knife, of a gage, 80 feeding means to engage one side of the stock, and a device to engage the other side of the stock mounted for rotary movement in a plane substantially transverse to the plane in which the stock moves as it is fed to the knife, said device being arranged to coöperate with said means in feeding the stock and also acting to move the stock laterally against the gage. 85

4. In a machine of the class described, the combination with a skiving knife, of a gage, 90 a feed roll for advancing stock to said knife, and a roll mounted for rotary movement in a plane substantially transverse to the plane of movement of the stock and acting to advance the stock and also to force the stock 95 against said gage.

5. In a machine of the class described, the combination with a skiving knife, of a gage, 100 a feed roll to act on one side of the stock, and a roll to act on the other side of the stock and rotatable in a plane substantially transverse to the plane of movement of the feed roll to feed the stock and force it against said gage.

6. In a machine of the class described, the 105 combination of a skiving knife, a gage, a feed roll for advancing stock to the knife, and a roll supported for movement about an axis arranged at an angle to the axis of said feed roll and constructed to move the stock 110 in a direction to maintain it in engagement with said gage while it is being fed to the knife.

7. In a skiving machine, the combination of a skiving knife, a gage, a feed roll for advancing stock to the knife, and a roll supported for movement about an axis arranged substantially parallel with the plane of the stock and at an angle to the axis of the feed roll and acting to maintain the 120 stock against said gage while it is being fed to the knife. 115

8. A machine of the class described having in combination, a skiving knife, a gage, a feed roll for acting on one side of stock, 125 and an auxiliary feed roll for acting on the opposite side of the stock arranged to hold the stock against said gage, while it is being fed to the knife, said auxiliary feed roll having a beveled periphery. 130

9. A machine of the class described having in combination, a skiving knife, a gage, a feed roll for acting on one side of stock, and an auxiliary feed roll for acting on the opposite side of the stock arranged to hold the stock against said gage, while it is being fed to the knife, said auxiliary feed roll having a beveled periphery provided with incisions. 70
10. A skiving machine having, in combination, a knife, a gage, a main feed roll, and an auxiliary feed roll having its axis arranged substantially at right angles to the axis of the main feed roll, said auxiliary feed roll being constructed to hold the stock against said gage while it is being fed to the knife. 75
11. A skiving machine having, in combination, a knife, a gage, a main feed roll, actuating means therefor, and an auxiliary feed roll provided with a beveled periphery scored obliquely and having its axis arranged substantially at right angles to the axis of the main feed roll, said auxiliary feed roll acting to force the stock against said gage. 80
12. In a machine of the class described, the combination of a skiving knife, a work support, a gage, and driven means for advancing stock in a direction to hold it against said gage, while it is being fed to the knife, arranged to yield in response to variations in the thickness of stock. 85
13. In a machine of the class described, the combination of a skiving knife, a gage, a main feed roll and an auxiliary feed roll operating to hold the stock against said gage, while it is being fed to the knife, and arranged to yield to accommodate stock of varying degrees of thickness. 90
14. In a machine of the class described, the combination of a skiving knife, a gage, a main feed roll, an auxiliary feed roll operating to hold the stock against said main feed roll and to crowd the stock against the gage while it is being fed to the knife, and a pivotal support for said auxiliary feed roll arranged to yield for accommodating stock of varying degrees of thickness. 95
15. In a skiving machine, the combination of a knife, a work support, a gage, and means for advancing stock and forcing it against said gage, said means and gage being supported for yielding movements relatively to said work support in response to variations in the thickness of stock. 100
16. In a skiving machine, the combination of a skiving knife, a work support, a gage, a feed roll and operating means therefor constructed and arranged to impart to the stock movements to hold it against said gage as it is being fed to the knife, a yoke for supporting said feed roll, and pivotal means for supporting said yoke. 105
17. In a skiving machine, the combination of a skiving knife, a work support, a gage, a feed roll and operating means therefor constructed and arranged to hold stock against said gage as it is being fed to the knife, a yoke for supporting said feed roll, a pivotal support for said yoke, and yielding means acting on the yoke for holding said feed roll upon the stock. 110
18. In a skiving machine, the combination of a skiving knife, a work support, a gage, a feed roll and operating means therefor constructed and arranged to impart to the stock movements to hold it against said gage as it is being fed to the knife, a yoke for supporting said feed roll and gage, and pivotal means for supporting said yoke. 115
19. The combination of a skiving knife, a work support, a gage, a feed roll and operating means therefor constructed and arranged to impart to the stock movements to hold it against said gage as it is being fed to the knife, pivotal supporting means for said feed roll, a yielding device acting thereon for moving said feed roll toward the work support, and means for adjustably determining the extent of the movement imparted to the feed roll by said yielding device whereby the feed roll may be positioned different distances from said work support in accordance with variations in the thickness of the stock. 120
20. In a machine of the class described, the combination of a skiving knife, a main feed roll, a gage, an auxiliary feed roll having a beveled periphery and actuating means therefor constructed to hold stock against the gage as it is fed to the knife, a support for the auxiliary feed roll, and means permitting adjustment to vary the angle presented by the beveled periphery of said roll and the surface of the main feed roll. 125
21. In a machine of the class described, the combination of a skiving knife, a main feed roll, a gage, an auxiliary feed roll having a beveled periphery and actuating means therefor constructed to hold stock against the gage as it is fed to the knife, a support for the auxiliary feed roll, and means permitting adjustment to vary the angle presented by the beveled periphery of said feed roll and the surface of the main feed roll and also to vary the space between said rolls. 130
22. A machine of the class described having, in combination, a skiving knife, a main feed roll, a gage, a power-driven auxiliary feed roll arranged to rotate in a plane transverse to the plane in which the stock moves as it is fed to the knife for holding the stock against the gage, and yielding means for supporting said auxiliary feed roll. 135
23. A machine of the class described having, in combination, a skiving knife, a main feed roll, a gage, a power-driven auxiliary feed roll, a yoke for supporting said feed roll, and pivotal support for said yoke. 140

feed roll arranged to rotate in a plane transverse to the plane in which the stock moves as it is fed to the knife for holding the stock against the gage, and yielding means 5 for supporting said gage and auxiliary feed roll for simultaneous movement toward and from the main feed roll.

24. In a skiving machine, the combination of a skiving knife, a gage, a feed roll for 10 advancing the stock to the knife, and a roll supported for movement about an axis substantially parallel to the line of feed and adapted to maintain the edge of the stock against the gage while said stock is being 15 operated upon by said knife.

25. In a skiving machine, the combination of a skiving knife for acting upon the stock, a gage, means for feeding the stock in a direction parallel to the face of the gage, and 20 means rotating in a plane substantially transversely of the line of feed for crowding the edge of the stock against the gage.

26. In a skiving machine, the combina-

tion of a skiving knife for acting upon the stock, a gage, means for feeding the stock 25 in a direction parallel to the face of the gage, and power actuated means moving in a plane substantially transversely of the line of feed for crowding the edge of the work against the gage.

27. In a skiving machine, the combination of a knife, an edge gage, a feed roll adapted to advance the stock in a substantially horizontal plane and an auxiliary feed roll rotatable about a horizontal axis in a path 35 the plane of which forms an angle with the direction of feed whereby the work is continually crowded against the edge gage during the feeding movement.

In testimony whereof I affix my signature 40 in presence of two witnesses.

HARRY LYON.
